CONNECTED SECTIONAL TABLE

Filed Dec. 1, 1949

Inventor

PHILIP COHEN

Harry Langsam

Attorney

When the frame of the section B is completely assembled, a hardwood top of two inch strips suitable held together is laid over the frame and secured thereto by bolts passing through the apron holes 18 and the top cross brace holes 28. The sections of the top are joined by a ship lap joint.

The table may be extended by joining additional sections B thereto. A single pair of legs E and a single pair each of top and bottom cross braces are common to both sections at the junction. The ends of the aprons D of the added section B abut and are joined to the end of the finished section, as shown in Fig. 8.

It is seen that by virtue of the peculiar end formation of the aprons in conjunction with the use of channel members for the legs and cross braces, I obtain a construction which is extremely simple to manufacture and assemble and which is light, strong and inexpensive.

Although my invention has been described in considerable detail, such description is intended as being illustrative rather than limiting, since the invention may be variously embodied, and the scope of the invention is to be determined as claimed.

I claim as my invention:

A sectional table, comprising a rectangular hardwood top having corners, a pair of angle steel side aprons, a top cross brace of steel channel attached to each end of said table top and to the middle of said table top, a leg of steel channel at each corner of said top, said side

aprons, top braces and said legs having an end joined together at each corner, and a bottom cross brace connecting the legs at each end of said table, each side apron having a vertical flange whose upper and lower portions are bent to form upper, and lower flanges in horizontal planes at opposite right angles to the middle portion of the vertical flange, and cut away portions in said lower horizontal flanges to interlock and form a stiffener between said legs, said upper horizontal flanges being in the same plane with the top brace member, and bolt locking means for connecting said aprons, cross braces and top with said leg members.

PHILIP COHEN.
